UNITED STATES PATENT OFFICE.

THOMAS CARDWELL, OF SEDALIA, MISSOURI.

THERMOSTATIC STEAM TRAP.

Application filed March 20, 1922. Serial No. 545,311.

To all whom it may concern:

Be it known that I, THOMAS CARDWELL, a citizen of the United States, and a resident of the city of Sedalia, county of Pettis, and State of Missouri, have invented a certain new and useful Improvement in Thermostatic Steam Traps, of which the following is a specification.

This invention relates to thermostatic steam traps for collecting and automatically discharging water of condensation in steam heating systems, and it relates more particularly to thermostatic steam traps of the kind used in connection with steam heating systems for railway cars.

The principal objects of the present invention are simplicity and cheapness of construction, certainty of operation and compactness of design; and the invention consists in the parts and combinations of parts hereinafter described and claimed.

In the accompanying drawing, which forms part of this specification and wherein like numerals indicate like parts in the several views,

Fig. 1 is a plan view of a thermostatic steam trap embodying my invention, the trap cover being removed and the anchor for the thermostatic rod being shown in section;

Fig. 2 is a vertical cross-section through the trap on the line 2—2 in Fig. 1; and

Fig. 3 is a vertical cross-section through said trap on the lines 3—3 in Fig. 1.

The thermostatic steam trap shown in the accompanying drawing comprises a shell or box 4, preferably of cast iron, provided with a removable cover plate 5. The shell or casing 4 is provided in one side wall, adjacent to one end thereof, with an inlet 6 which communicates with the steam pipe 7 of a steam heating system, preferably of the kind used for heating railway cars.

The shell 4 has a circular recess or outlet chamber 8 formed in its bottom, said chamber being located at the end opposite from the inlet 6 and communicating through a horizontal outlet passageway 9 with an outlet or discharge pipe 10. The drain chamber 8 is closed by means of a lift-valve 11 having a depending stem 12 surrounded by a coil spring 13, which rests on the bottom of the chamber 8 and bears against the underside of the valve 11, thus tending to lift the same off its seat. The drain valve 11 is provided with an upstanding tubular stem 14 arranged for sliding movement in a cir-

cular opening in the horizontal web portion on an inverted U-shape bracket 15, which straddles said valve and is provided with base flanges secured to the bottom of the trap chamber by means of screws.

A pin 16, having a hemispherical head 17 provided with a circular base 18 of slightly larger diameter, is slidably mounted in the upper end of the tubular valve stem 14; and a coil spring 19 is arranged within the bore of said stem, between the lower end of the pin 16 and the bottom of said bore, and tends to force said pin upwardly. A pin 20 extends through alined holes in the upright valve stem 14 and an elongated slot 21 in the pin 16 and serves to limit the upward movement of said valve-pin 16.

Located within the steam pipe line 7 is a thermostatic member in the form of a cylindrical rod 22, preferably of rolled zinc. The inner end of the thermostatic rod 22 is provided with a threaded extension 23 which is slidably supported in an axial bore in the spider of a union 24 that connects the adjacent ends of the pipe sections of the steam line 7; and said extension is provided on opposite sides of said spider with adjusting nuts 25, whereby said rod is adapted to be adjusted longitudinally of said steam pipe line and locked in the desired position of adjustment. The end portion of the thermostatic rod 22 projects into the trap through the inlet 6 thereof and has an extension 26 threaded thereon. This extension 26 has a pivotal connection with an arm 27 arranged within the trap for horizontally swinging movement. The arm 28 has one end pivotally supported on a pivot-pin 29 located adjacent to the inlet end of the trap-chamber and in alinement with the axis of the lift-valve 11. This pivot-pin has its lower end supported in a boss in the bottom of the trap chamber and has its upper end journaled in a lug that projects horizontally from the end wall of said chamber. The operating arm 28 extends beyond the axis of the valve 11; and the thermostatic rod is pivotally connected to said arm, adjacent to the pivoted end thereof, by means of a pin 30 that extends vertically through alined holes in said arm and in the extension 27 of said rod.

The valve 11 is closed by means of a lug 31 on the underside of the free outer end of the operating arm 28. This lug is located in the plane of the hemispherical head 17 of

the valve-pin 16 in the raised position thereof and is provided at its forward end with a curved or beveled surface adapted to engage said head when the operating arm is 5 swung across the same, thereby depressing said pin and closing the valve 11. The valve 11 is automatically locked in its closed position by means of a trigger 32 arranged for horizontal sliding movement in the 10 spaced upright arms of a U-shaped supporting bracket 33. This bracket is secured to the guide bracket 15 in position to enable the trigger to engage the shouldered head of the valve-pin 16, thereby locking the valve 11 in 15 its closed position. A coil spring 34 is sleeved on the trigger or lock-rod 32, between the head thereof and the adjacent arm of the supporting bracket therefor, and tends to force the head of the lock rod into 20 engagement with the head of the valve-pin 16 when the same is depressed by the action of the operating arm. The trigger or plunger rod 32 is provided at its rear end with an upstanding finger 35 located in a 25 path of a lateral extension 36 on the forward end of the operating arm 28, whereby said extension during the rearward movement of said arm is adapted to engage said finger, thereby withdrawing the locking pin 30 from engagement with the valve-pin 16 and permitting the valve 11 to be lifted off its seat by the pressure of its supporting spring 13. The finger 35 is adjustable longitudinally of the trigger 32 and is held 35 in the desired position of adjustment by means of a set screw 37.

The operation of the valve mechanism above described is as follows: Assuming that the valve 11 is open live steam passes 40 through the steam pipe 7 and causes a gradual elongation of the thermostatic rod 22, which action swings the free outer end of the operating arm 28 towards the valve-pin and forces the beveled forward end of 45 the lug 30 into engagement with the hemispherical head of said pin, thereby depressing the same and causing the drain valve 11 to seat and close the discharge opening. As condensation proceeds and the cool 50 water collects within the trap and reaches the level of the thermostatic rod 22, said rod gradually contracts and swings the arm clear of the pin 16. Continued movement of the operating arm causes the lateral 55 projection 36 thereof to engage the adjustable finger 35 of the lock-pin 32 and disengage the same from the valve-pin 16, thereby permitting the same to be lifted off its seat by the pressure of the spring 13. The water 60 of condensation is then blown out through the discharge pipe 10 by the pressure of the live steam, which causes the thermostatic rod to again expand and actuate the arm to again 65 close the valve 11.

65 My device is applicable to steam heating

systems generally. The locking of the drain valve until the operating arm is swung clear thereof permits the valve to open with a single quick stroke, thereby enabling the water and foreign matter to be quickly 70 discharged, as distinguished from devices having drain valves that open gradually and permit slow dripping of the water which freezes in cold weather and renders said valve inoperative. The valve can be adjusted to open at the desired temperature 75 by adjusting the finger 35 longitudinally of the lock-rod; and the spring support 17 for the valve pin 16 serves to seat the drain valve regardless of wear of the valve or the 80 seat therefor.

It is obvious that numerous changes may be made without departing from the invention and I do not wish to be limited to the precise construction shown.

What I claim is:

1. In a steam heating system a thermostat steam trap therein, said trap comprising a casing having an inlet in communication with said system and an outlet for the discharge of water of condensation, a valve in said outlet, means tending to open said valve, a thermostat, means operating by said thermostat for closing said valve, and means for automatically locking said valve in its closed position, said locking means being adapted to be actuated by said valve closing means to unlock said valve after the valve closing means is disengaged therefrom.

2. In a steam heating system, a steam trap therein, said trap comprising a casing having an inlet in communication with said system and an outlet for the discharge of water of condensation, a lift-valve in said outlet, means tending to open said valve, a thermostat, an arm pivoted in said casing and adapted to engage said valve to close the same, said arm being operatively connected to said thermostat to be actuated thereby, and a trigger for automatically locking said valve when closed, said trigger being adapted to be actuated by said arm to unlock said valve after the arm is disengaged therefrom.

3. In a heating system, a steam trap therein, said trap comprising a casing having an inlet in communication with said system and an outlet for the discharge of water of condensation, a lift-valve in said outlet, means tending to open said valve, a thermostat, and a lever movable across said valve and adapted to gradually close the same, said lever being operatively connected to said thermostat to be actuated thereby.

4. In a heating system, a steam trap therein, said trap comprising a casing having an inlet in communication with said system and an outlet for the discharge of water of condensation, a lift-valve in said outlet, means

- tending to open said valve, a thermostat, a lever movable across said valve and adapted to gradually close the same, said lever being operatively connected to said thermostat to be actuated thereby, means for automatically locking said valve in its closed position, and means carried by said lever for releasing said locking means after said lever is clear of said valve.
5. In a steam heating system, a steam trap therein, said trap comprising a casing having an inlet communicating with said system and having an outlet open to the atmosphere, a valve in said outlet, means tending to open said valve, a thermostat, means operated by said thermostat for closing said valve, means for automatically locking said valve when closed, and means carried by said valve closing means for releasing said valve locking means after the valve closing means is disengaged from said valve.
10. 6. In a steam heating system, a steam trap therein, said trap comprising a casing having an inlet communicating with said system and an outlet for the discharge of water of condensation, a lift-valve in said outlet, means tending to open said valve, a spring supported pin on said valve, a lever arm adapted to engage said pin to close said
15. valve, a thermostat for actuating said lever arm, and a spring pressed pin adapted to engage said valve-pin in the closed position on said valve to lock the same in said position, said locking pin being adapted to be engaged by said lever to unlock said valve after the lever is disengaged therefrom.
20. 7. A steam trap for steam heating systems, said trap comprising a casing having an inlet adapted to communicate with said system and an outlet for the discharge of water of condensation, a lift-valve in said outlet, a spring tending to open said valve, a spring-supported pin carried by said valve, a lever arm arranged for swinging movement across said pin to depress the same and thereby close said valve, a thermostat in said inlet and operatively connected to said lever for actuating the same, a spring pressed lock-rod adapted to engage said pin in the closed position of said valve to lock the same in said position, said lock rod being adapted to be disengaged from said pin to release said valve after said lever is swung clear of said pin.
25. Signed at St. Louis, Missouri, this 18th day of March, 1922.

THOMAS CARDWELL.
